UNITED STATES PATENT OFFICE.

THOMAS C. HARGRAVE, OF BOSTON, MASSACHUSETTS.

IMPROVEMENT IN CAR-AXLE LUBRICATORS.

Specification forming part of Letters Patent No. 42,577, dated May 3, 1864.

To all whom it may concern:

Be it known that I, THOMAS C. HARGRAVE, of Boston, in the county of Suffolk and State of Massachusetts, have invented a certain new and useful Improvement in Lubricators for Car-Wheels; and I do hereby declare the following to be a full, clear, and exact description thereof, reference being had to the accompanying drawings, and to the letters of reference marked thereon, in which—

Figure 1 is a vertical section of the lubricator through the line *x x*, Fig. 2; and Fig. 2 is a vertical section through the line *y y*, Fig. 1.

My invention and improvement consists in the combination and arrangement of an outside spring with the lubricating wheel or roller, so as to allow of the adjustment of the lubricating-wheel without opening the journal box, as hereinafter to be more fully set forth.

a is the car-wheel. *b* is the journal of the car-wheel axle. *c* is the lubricating wheel or roller. *d* is the support to which the lubricating-wheel is attached. *e* is a rod connecting the lubricating-wheel, by means of the support *d*, with the spring *f*, outside of the journal-box. *g* is the oil or other lubricating substance. *h* is the lid or door of the journal-box, by means of which admission is obtained to the inside of the journal-box for replenishing the oil or other lubricating substance when necessary. *i* is a nut for adjusting the lubricating-wheel from the outside of the journal-box. *j* is the housing of the journal-box, and *k* is a chamber for containing the end of the

support *d* and the rod *e*, said chamber having a free communication with the interior of the journal-box.

Upon the lower part of the rod *e* is cut a screw-thread. The rod is then screwed into a hole drilled into the support *d*, so that the rod may be readily detached from the support and the lubricating wheel or roller conveniently removed from the journal box when required. The pressure of the spring *f* may be regulated at will by means of the nut *i*, and keeps the lubricating wheel or roller always in contact with the journal, thus furnishing a constant supply of oil or other lubricating substance to the journal. The housing *j* and chamber *k* are cast in one piece with an opening or communication between them for the end of the support *d* to pass through and sufficiently large to allow the support to move freely up and down as it is acted upon by the spring *f*, with which it is connected by the rod *e*.

Having thus fully described my invention, what I claim, and desire to secure by Letters Patent, is—

The combination and arrangement of the outside spring, *f*, the rod *e*, the support *d*, and the lubricating wheel or roller *c* with the journal *b* and housing *j*, substantially as and for the purpose set forth.

T. C. HARGRAVE.
